US00D838731S

(12) **United States Design Patent** (10) **Patent No.:** **US D838,731 S**
Pillalamarri et al. (45) **Date of Patent:** **** Jan. 22, 2019**

(54) **DISPLAY SCREEN WITH A GRAPHICAL USER INTERFACE**

(71) Applicant: **INSULET CORPORATION**, Billerica, MA (US)

(72) Inventors: **Sandhya Pillalamarri**, Methuen, MA (US); **Jorge Borges**, Billerica, MA (US); **Peter Syromiatnikov**, Billerica, MA (US)

(73) Assignee: **INSULET CORPORATION**, Billerica, MA (US)

(**) Term: **15 Years**

(21) Appl. No.: **29/658,907**

(22) Filed: **Aug. 3, 2018**

Related U.S. Application Data

(62) Division of application No. 29/606,873, filed on Jun. 8, 2017, now Pat. No. Des. 826,957.

(57) **CLAIM**

The ornamental design for a display screen with a graphical user interface, as shown and described.

DESCRIPTION

FIG. 1 is a front view of a display screen with a graphical user interface showing our new design; and, FIG. 2 is a front view of a second embodiment thereof. The outermost broken line illustrates a display screen and forms no part of the claimed design. The remaining broken lines illustrate portions of the graphical user interface that form no part of the claimed design.
